(57) **CLAIM**

The ornamental design for a reagent cartridge, as shown and described.

DESCRIPTION

FIG. 1 is a top isometric view of a reagent cartridge;
FIG. 2 is a right side view thereof;
FIG. 3 is a left side view thereof;
FIG. 4 is a rear view thereof;
FIG. 5 is a front view thereof;
FIG. 6 is a top view of thereof;
FIG. 7 is a bottom view of thereof;
FIG. 8 is a bottom isometric view;
FIG. 9 is another top isometric view;
FIG. 10 is another bottom isometric view; and,
FIG. 11 is a cross sectional view taken along line 11-11
shown in FIG. 6.
